UNITED STATES PATENT OFFICE.

BRYANT H. MELENDY, OF BATTLE CREEK, MICHIGAN.

DOUGH-KNEADING MACHINE.

SPECIFICATION forming part of Letters Patent No. 423,619, dated March 18, 1890.

Application filed August 24, 1889. Serial No. 321,808. (No model.)

To all whom it may concern:

Be it known that I, BRYANT H. MELENDY, of Battle Creek, in the county of Calhoun and State of Michigan, have invented a new 5 and Improved Dough-Kneading Machine, of which the following is a full clear, and exact description.

The invention relates to dough-kneading machines such as shown and described in 10 Letters Patent No. 381,631, granted to me April 24, 1888.

The object of the present invention is to provide a new and improved dough-kneading machine, which is simple and durable in construction and very effective in operation.

The invention consists in certain parts and details and combinations of the same, as will be described hereinafter, and then pointed out in the claims.

Reference is to be had to the accompanying drawings, forming a part of this specification, in which similar letters of reference indicate corresponding parts in all the figures.

Figure 1 is a front view of the improvement, with parts in section and broken away. Fig. 2 is a side elevation of the same. Fig. 3 is a side elevation of the crank-arm. Fig. 4 is a side elevation of the crank-handle. Fig. 5 is a sectional plan view of the same on 30 the line $x-x$ of Fig. 4. Fig. 6 is a sectional side elevation of a modified form of the scraper, and Fig. 7 is a transverse sectional elevation.

The improved dough-kneading machine is 35 provided with a frame A, having the sides B connected with each other at the rear by a transversely-extending bottom piece C and by a transversely-extending inclined partition D, on which is placed the metallic plate E, secured in place by a screw E', as is plainly shown in Figs. 1 and 7.

Between the sides B is held a roller F, provided with the trunnions F' and F'', mounted to turn in suitable recesses B', formed in the 45 sides B. The upper ends of the recesses B' connect with outwardly-extending slots B'', in which are held the blocks G G', fulcrumed on pins or screws G'', secured in the side edges of a transversely-extending front board H, held between the sides B and pivoted near its upper end on the screws H', secured in the sides B, as is plainly shown in Figs. 1, 2, and 7.

Hooks I are pivoted on the outsides of the blocks G and G', and are adapted to engage pins I', screwed into the outsides of the sides B. The hooks I serve to lock the blocks G and G' and the front board H in place, so that the trunnions F' and F'' are prevented from moving out of the recesses B', and the 60 lower edge of the front board H rests on the top of the roller F.

When the operator desires to remove the roller F, he unhooks the hooks I from the pins I' and then swings the blocks G and G' 65 outward, so that the front board H swings with the said blocks into the position shown in dotted lines in Figs. 2 and 7. The recesses B' and the slots B'' are thus uncovered and the trunnions F' and F'', with the roller F, can 70 be lifted out of the same.

Against the under side of the roller F presses a scraper J, secured on a transversely-extending beam J', adjustably secured to the under side at the front of the sides B. The scraper J is secured in place by set-screws J''. As shown in Fig. 6, an inclined slot is formed in the beam J', in which the scraper J is set, small nails being driven through the scraper J and the beam to hold the said scraper in place. 80 By arranging the scraper as shown, when the dough is in the machine and passes out between the plate E and the roller F, it exerts an outward pressure against the roller, so that even if the trunnions of the roller have 85 become worn the roller remains in about the same position relatively to the scraper.

One of the trunnions F' is provided with a conical offset F'', on which fits a crank-arm K, provided with a cross-shaped offset K', in 90 which are formed the slots K'' and K''', crossing each other, as is plainly shown in Fig. 3. Either of the slots K'' or K''' is adapted to be engaged by a projection L', formed near the upper end of a handle L, serving to turn the 95 roller F, as is hereinafter more fully described.

On the projection L' is formed a hook L'', adapted to engage the back of the cross K', so as to securely lock the handle L to the crank K.

In the conical offset F'' are formed a number of recesses F''', adapted to be engaged by correspondingly-shaped offsets or ribs K''', formed on the crank-arm K. When the latter is driven onto the offset F'', so that the ribs 105 K''' fit in the said recesses F''', the crank-arm

is securely held in place on the end of the trunnion F'.

The operator may at any time conveniently move the handle L, for engaging the offset L' with one of the slots K² or K³, so that the hook L² rests against the rear of the cross K' of the said arm K, thus locking the handle to the arm K. By placing the handle L with its offset L' in the horizontal slot K² the handle L is made longer than when the offset L' is placed in the vertical slot K³. By this simple means the handle L is lengthened or shortened in relation to the trunnion F'.

To one of the sides B is secured a bracket 5 O, provided with the inwardly-extending projections O' and O², adapted to rest on top of a table Q, while the under side of the latter is engaged by a screw P, screwing in a projection O³, secured on the lower end of the bracket O.

Other suitable means may be employed for supporting the frame A above the table or bench.

The dough is placed in the frame A between the sides B, and rests against the plate E and the front board H and also on top of the roller F. The further operation is similar to the one described in the patent above referred to.

Having thus described my invention, what I claim as new, and desire to secure by Letters Patent, is—

1. In a dough-kneading machine, the combination, with a frame provided with sides and cross-pieces, of a roller journaled in the said frame, blocks held on top of the roller-trunnions, and a front board pivoted between the said sides and on which the said blocks are pivoted, substantially as shown and described.

2. In a dough-kneading machine, the combination, with a frame provided with sides and cross-pieces, of a roller journaled in the said frame, blocks held on top of the roller-trunnions, a front board pivoted between the said sides and on which the said blocks are pivoted, and means, substantially as described, for locking the said blocks and a front board in place, as set forth.

3. In a dough-kneading machine, the combination, with a frame provided with sides and cross-pieces and open at the top and bottom, of a transversely-inclined partition held between the said sides, a metallic plate held in front of the said partition, a roller journaled in the said sides, a front board pivoted between the said sides and extending with its lower edge to the said roller, and means for locking the board in position, substantially as shown and described.

4. In a dough-kneading machine, the combination, with a frame provided with sides and cross-pieces and open at the top and bottom, of a transversely-inclined partition held between the said sides, a metallic plate held in front of the said partition, a roller jour-

naled in the said sides, a front board pivoted between the said sides and extending with its lower edge to the said roller, means for locking the board in position, and a scraper held on the under side of the said sides and in contact with the lower part of the said roller, substantially as shown and described. 70

5. In a dough-kneading machine, the combination, with a frame provided with sides and cross-pieces and open at the top and bottom, of a transversely-inclined partition held between the said sides, a metallic plate held in front of the said partition, a roller journaled in the said sides, a front board pivoted 80 between the said sides and extending with its lower edge to the said roller, a scraper held on the under side of the said sides and in contact with the lower part of the said roller, and blocks pivoted on the said front board 85 and fitting into recesses in the said sides to hold the roller in place, substantially as shown and described.

6. In a dough-kneading machine, the combination, with a frame provided with sides and cross-pieces and open at the top and bottom, of a transversely-inclined partition held between the said sides, a metallic plate held in front of the said partition, a roller journaled in the said sides, a front board pivoted 90 between the said sides and extending with its lower edge to the said roller, a scraper held on the under side of the said sides and in contact with the lower part of the said roller, blocks pivoted on the said front board 100 and fitting into recesses on the said sides to hold the roller in place, and hooks held on the said blocks and adapted to be hooked on pins on the said sides, substantially as shown and described. 105

7. In a dough-kneading machine, the combination, with a frame and a roller journaled therein, of a crank-arm secured on one of the trunnions of the said roller and provided with crossing slots, a crank-handle provided 110 with a projection adapted to engage one of the said crossing slots, and a hook formed on one end of the said projection, substantially as shown and described.

8. In a dough-kneading machine, the combination, with a crank-arm secured to the roller-trunnion and provided with crossing slots, of a crank-handle provided with a projection adapted to engage one of the said slots, substantially as shown and described. 115 120

9. In a dough-kneading machine, the combination, with a frame and a roller journaled therein, having one of its trunnions provided with a conical offset having longitudinal recesses F³, of a crank-arm provided with crossing slots and with ribs K⁴, substantially as shown and described. 125
